UNITED STATES PATENT OFFICE.

NOEL H. LYSONS, OF MONTREAL, QUEBEC, CANADA, ASSIGNOR TO WESTERN ELECTRIC COMPANY, INCORPORATED, OF NEW YORK, N. Y., A CORPORATION OF NEW YORK.

CALLING DIAL.

Application filed August 29, 1924. Serial No. 734,865.

This invention relates to calling dials in general and more specifically to improvements in a calling dial of the type disclosed in Patent No. 1,279,352 issued to A. E. 5 Keith, wherein the springs are mounted in a pile-up on the mounting plate and secured by screws which when unfastened cause the springs to separate from each other and wherein the speed governor is mounted in 10 separately detached parts on the dial mounting plate.

Such construction, holds the repairs and maintenance cost of such a dial very high since the dial must be taken apart for the 15 replacement or repair of a minor part.

The object of this invention is to provide a dial which will be simple, efficient, cheap to manufacture and in which parts which in service become inoperative are readily 20 replaceable or renewable, thereby reducing the cost of maintenance to a minimum.

A feature of the invention resides in the provision of a bracket for supporting the impulse cam and governor mechanism in a 25 manner to form a unit which may be readily applied to or removed from the mounting plate.

Another feature is the provision of a 30 bracket for supporting the impulse and shunt springs of the dial together with the provision of means in the bracket whereby the springs may be readily disposed in adjustment with their associated shunt and impulse operating mechanism.

35 Another feature is the provision of an auxiliary stop whereby the motor spring is held in adjustment when the governor unit is removed.

Other features of the invention and advantages will appear from the following 40 description and by the claims appended thereto, reference being had to the accompanying drawings in which Fig. 1 is a plan view of the dial with portion of the finger wheel cut away to show the auxiliary stop more clearly. Fig. 2 is a back view thereof. Fig. 3 is a plan assembly view of the 45 governor unit. Fig. 4 is a side view thereof. Fig. 5 is a plan assembly view of the spring unit and Fig. 6 is a side view thereof showing the bracket in adjusted position on the mounting plate.

The calling dial in which this invention 50 is particularly well adapted for use generally consists of a supporting plate 10 in

the central portion of which is rotatably mounted the shaft 13 of a finger wheel 11. A motor spring 12 having one end portion hooked on the plate 10 and the other end mounted in the slotted end portion of shaft 60 13 is provided for returning the finger wheel 11 to normal position against the resistance of a speed governor mechanism shown in Figs. 2, 3 and 4.

The finger wheel 11 carries a clutch mechanism (not shown) which permits the movement of the finger wheel in a clock-wise direction, ineffectively with respect to the impulse cam 15, in a manner described in the 65 patent above referred to. The impulse wheel 15 is mounted on one end of shaft 16 and is held securely thereon by means of nuts 17 and 18. A pinion 19 secured on the shaft 16 is disposed in operable relation

70 to a gear carried by the driven portion of the clutch mechanism above referred to and is adapted to operate the impulse wheel 15 upon each return movement of finger wheel 11. The shaft 16 carries a worm gear 75 20 which is disposed in operable relation with the screw 21 integrally formed on the governor shaft 22. This shaft carries two

centrifugally operated weights 23 and 24 which cooperate with the stationary drum 33 for controlling the speed of the impulse 80 85 cam 15 during the return movement of finger wheel 11. This shaft 22 is journaled on adjustable bearings 25 and 26 each of which is screwed on the bracket 27. Integrally formed with bracket 27 and extending perpendicularly therefrom, there is provided 90 an arm 28 on which one end of the shaft 16 is journaled. The arm 29 is held securely on the bracket 27 by means of screw 30 and

locating pins 31 and 32 and is adapted for 95 supporting the upwardly extending end of shaft 16. By removing the screw 30 the arm 29 may be removed to permit the removal of the shaft 16 carrying the cam 15, wheel 20 and pinion 19, for purposes of 100 replacement of any of these parts or repair.

Bracket 27 is held securely on the supporting plate 10 by means of screws 34 and 35 and locating pins 36 and 37 respectively. By means of this arrangement, the bracket 105 27 and the governor mechanism carried thereby may be conveniently mounted or removed as a unit from the supporting plate 10 for repairs or replacement of parts.

The spring assembly unit consists of a 110

U-shaped bracket 45 on which the impulse springs 46 and 47 are mounted and insulated from the shunt spring 48, 49 and 50 by means of insulating strips 51. The bracket 45 is held securely on the supporting plate 10 by means of screws 38 and 39 and locating pins 40 and 41, one of them being shown in Fig. 6.

A finger stop 42, securely attached on the plate 10 is provided with an inwardly extending arm 43 which cooperates with the pin 44 carried by the finger wheel 11 to form an auxiliary stop to prevent the unwinding of the motor spring 12 as would otherwise occur when the pinion 19 is removed from the usual stop lug as the governor unit is removed from the supporting plate.

What is claimed is:

- 20 1. In a calling dial, a mounting plate, impulse springs carried by said mounting plate, a finger wheel associated with said mounting plate, driving gear mechanism carried by said mounting plate and actuated by said finger wheel for operating said springs, a bracket a governor for controlling the speed of said spring actuating mechanism mounted on said bracket, a pinion thereon meshing with said gear mechanism, a spring actuating element on said bracket, a worm gear on said bracket, a worm screw on said bracket with which said worm gear meshes, and means for attaching said bracket and all of the elements carried thereby to the supporting plate as a unit.
- 25 2. In a calling dial, a mounting plate, impulse springs carried by said mounting plate, a finger wheel associated with said mounting plate, driving gear mechanism carried by said mounting plate and actuated by said finger wheel for operating said springs, a governor for controlling the speed of said gear mechanism, a bracket carrying said

governor and removable from the supporting plate as a unit, an auxiliary stop carried by the finger wheel, and a fixed member which engages said stop to hold the motor spring of the driving mechanism properly tensioned while the bracket is removed from said mounting plate.

3. The combination with a governor mechanism, an impulse cam movable under control of said mechanism, impulse springs associated with said cam, a bracket for said governor mechanism and said cam, a supporting plate, registering means carried by said plate and said bracket for locating said impulse cam in adjustment relative to said springs, and means for securing said bracket on said plate.

4. In a calling dial, the combination with a finger wheel, a motor spring tensioned through the movement of said finger wheel, a plate, a finger stop mounted on said plate, and cooperating means carried by said finger wheel and said finger stop for holding said motor spring in adjustment.

5. In a calling dial, the combination with a mounting plate, an arcuated bracket having perpendicularly extending lugs on two end portions, a governor device journaled on said lugs, an arm extending in opposite direction to said lugs, a shaft having one end portion pivotally arranged in said arm, a pinion and a worm gear on said shaft engaging said device, an impulse cam carried by said shaft, and a support carried by said bracket for holding the opposite end portion of said pinion, the whole being readily attached to or removed from said plate as a unit.

In witness whereof, I hereunto subscribe my name this 25th day of August A. D., 1924.

NOEL H. LYSONS.
